UNITED STATES PATENT OFFICE.

HENRY D. DESHLER, OF BELVIDERE, NEW JERSEY.

DESIGN FOR A CASING FOR VENDING-MACHINES.

46,715.

Specification for Design.

Patented Dec. 1, 1914.

Application filed August 12, 1914. Serial No. 856,503. Term of patent 14 years.

To all whom it may concern:

Be it known that I, HENRY D. DESHLER, a citizen of the United States, residing at Belvidere, in the county of Warren and State of New Jersey, have invented a new, original, and ornamental Design for a Casing for Vending-Machines, of which the following is a specification, reference being had to the accompanying drawing, forming part thereof.

The figure is a perspective view of a casing for vending machines, showing my new design.

I claim:

The ornamental design for a casing for vending machines, as shown.

HENRY D. DESHLER.
